United States Patent

Des. 240,323
Patented June 22, 1976

240,323

LIGHTING FIXTURE

Robert E. Walker, Bellevue, and G. Thomas Henderson,
Bainbridge Island, Wash., assignors to Cascade Pacific
Lumber Co., Inc.

Filed July 17, 1974, Ser. No. 489,361

Term of patent 14 years

Int. Cl. D26—03

U.S. Cl. D48—31

FIG. 1

FIG. 3

FIG. 2

FIG. 4

FIG. 5

FIG. 1 is a perspective view of a lighting fixture incorporating our new design;

FIG. 2 is a top plan view thereof;

FIG. 3 is a front elevation view thereof;

FIG. 4 is a side elevation view thereof; and

FIG. 5 is a rear elevation view thereof.

The side of the article which is not shown is substantially identical to the side disclosed in FIG. 4. The bottom of the device is plain and unornamented.

We claim:

The ornamental design for a lighting fixture, substantially as shown and described.
